UNITED STATES PATENT OFFICE.

CECIL MASSEY, OF LITCHFIELD, ILLINOIS.

BURIAL CASKET.

Application filed July 2, 1925. Serial No. 41,190.

The present invention relates to burial caskets, and the object is to provide a novel structure whereby the interior of the casket is made water-proof or air sealed, the structure further being relatively inexpensive, and the necessity of a separate container for shipping or interment purposes being eliminated.

In the accompanying drawings:

10 Figure 1 is a perspective view of the casket.

Figure 2 is a cross sectional view of the same,

15 Figure 3 is a longitudinal sectional view, Figure 4 is a detail sectional view across one of the bottom reenforcing bars,

Figure 5 is a detail sectional view illustrating one of the locking latches,

20 Figure 6 is a view in elevation of one of said latches detached,

Figure 7 is a bottom plan view of the bottom,

Figure 8 is a plan view of the shipping-board.

25 In the embodiment disclosed, a casket is employed, comprising side walls 9 and a bottom 10, which extends beyond the side walls, as illustrated at 11, the bottom having downwardly inclined marginal portions 12. The

30 interior of the casket may be lined in any suitable manner, as indicated at 13, and a top 14 may be provided therefor. The side walls and top may be of any suitable configuration, and as expensively or cheaply

35 decorated as desired.

An air-tight and water-proof hood 14^a is employed that closes the casket and has downwardly inclined margins 15 adapted to rest upon and form a tight joint with the

40 margins 12 of the bottom. This hood has on its inner side and just above the inclined portions 15 a plurality of keeper lugs 16 adapted to be engaged by the hooked heads 17 of a plurality of holding latches. The

45 shanks 18 of these latches pass through openings 19 in the projecting portions of the bottom 11 and their lower ends have coiled springs 20 thereon that bear against abutment nuts 21 carried by the lower ends of the

50 shanks. The openings through which the shanks pass are of sufficient diameter to permit a slight lateral play to the shanks. It will be noted by a comparison of Figures 5 and 6 that the hooks of the heads 17 are on

55 opposite sides and that the other two sides do not have the hooked portions. The bot-

tom 10 is reenforced by transverse channel bars 22 and these bars are so arranged that they house the downwardly projecting portions of the latches.

60 For shipping purposes and the like, a shipping-board 23 is employed, preferably in the form of a frame, composed of longitudinal strips 25 and cross strips 26. This frame is placed beneath the assembled structure, and is secured thereto by hook bolts 27 that pass through the margins of the frame and engage over the upturned edges 28 of the hood.

65 In use, after the body has been placed in the casket, the heads 17 of the latches are turned so that the hooked portions thereof

will engage over the lugs 16, after which the hood is placed in position and will be automatically fastened by the hooks of the heads

70 17 engaging over the lugs 16, as shown in Figure 5. The casket is thus permanently

75 fastened and the hood constitutes an air-seal that will prevent the ingress of water. When arranged for shipping purposes, the

latches are turned so that the heads 17 will be inactive as illustrated in Figure 2. The

structure is then carried on the shipping-board 23 and the hook bolts engaged, as illustrated in Figures 2 and 3. When so ar-

75 ranged it will be evident that the parts will be securely fastened together.

80 From the foregoing, it is thought that the construction, operation and many advantages of the herein described invention will be ap-

85 parent to those skilled in the art, without further description, and it will be under-

90 stood that various changes in the size, shape, proportion and minor details of construction may be resorted to without departing from the spirit or sacrificing any of the advan-

95 tages of the invention.

What I claim, is:

1. The combination with a body-receiving casket having side walls, a bottom, and reinforcing channel bars extending across the underside of the bottom, of a hood for enclosing the side walls, and latches for securing the hood in place, said latches having portions housed in the ends of the channel bars.

100 2. The combination with a body-receiving casket having side walls and a bottom that projects beyond the side walls, of a hood for enclosing the side walls, said hood resting on the projecting portions of the bottom and having keepers adjacent to their resting points, spring actuated latches slidably

mounted in the projecting portions of the bottom between the side walls and hood for interlocking with said keepers to hold the hood in place, and reinforcing channel bars 5 extending across the bottom, the latches having portions projecting through the bottom and housed by the channel bars.

3. The combination with a body holding casket having side walls and a bottom projecting beyond the side walls, of a hood that encloses the side walls and rests on the projecting portion of the bottom, a shipping platform on which the bottom rests, and clamping devices connecting the lower margins of the hood and the shipping board for 10 holding the structure in assembled relation. 15

4. The combination with a body holding casket having side walls and a bottom projecting beyond the side walls and having a downwardly inclined margin, of a hood that 20 encloses the side walls and has a downwardly inclined margin that rests on the margin of the bottom, latches that are movably mounted in the projecting portions of the bottom and engage the hood to fasten the two together, a shipping board beneath the bottom, and hook bolts carried thereby and engaging over the free edge of the hood to 25 secure the same over the casket.

In testimony whereof, I affix my signature.

CECIL MASSEY.
